STRAIN CLAMP

Charles W. Kemper and John T. Kemper,
Hayward, Calif.

Application June 13, 1932. Serial No. 616,815

8 Claims. (Cl. 24—136)

This invention relates to cable clamping devices of the type shown in our U. S. Patent No. 1,811,942, and has for its objects improvements over the former structure whereby the device will meet the requirements of a strain clamp as required for power and other lines supported on poles.

In the drawing Fig. 1 is a side view of our improved cable clamp.

10 Fig. 2 is a vertical section of the clamp of Fig. 1.

Fig. 3 is an elevation showing the upper portion of a line pole with two of our improved clamps in position on a high power electric 15 cable.

Fig. 4 is a cross section of Fig. 1 taken along the line 4—4 thereof.

Fig. 5 is a cross section of Fig. 1 taken along the line 5—5 thereof.

20 In further detail the device comprises an inverted U-shaped metal shell 1 provided with an outwardly slanted portion 2 and a pair of rearwardly extending ears 3 pierced with aligned holes to receive a pin 4 of a yoke 5 or other connection 25 extending from a series of insulators 6 connected to the pole 7 as at 8.

This shell 2 is the main body member of the clamp and it is formed with hinge eyelets or loops 9 formed along both edges and spaced to receive 30 between them similar eyelets 10 of a cover shell 11 which forms with shell 1 a channel for a cable 12. The extreme end of the channel is flared slightly larger than the cable as at 20, and at the opposite end just beyond the slanted 35 portion 2 the cover shell 11 is curved downwardly or away from the axis of the device as at 11' so as to lead the cable as at 12' away from the run of the cable within the channel so that it can hang in a free untensioned loop 40 between two clamps used on a pole or may extend freely down (or up) to a transformer 13 carried on the pole and energized by the cable.

Within the larger U-shaped shell between the slanted wall 2 and the cable is a frictional pinching roller 14 preferably made of hard steel or extremely hard alloys and provided with a serrated concave surface 14' as indicated so that it will tightly grip both cable and wall 2 as the pull on the cable is exerted in direction of the 45 arrow.

This roller 14 is centrally apertured and fitted with a pin 15 projecting out beyond the sides of the roller into slots or recesses 16 formed in the opposite side walls of the ears 3, and which 50 recesses are apertured for passage of a cotter

pin 17 which may be inserted to hold the roller in released position as dotted at 14" or in the locked position of the roller shown in the drawing.

The two U-shaped shells which form the cable 60 channel are connected together by parallel hinge pins 18 passing through the eyelets or loops 9, 10, and one of these pins is permanently headed over, but the other is headed at one end only to start so that it may be easily withdrawn to 65 swing the shells open on the other pin, for free insertion of the cable, and when closed and the loose pin is reinserted through the eyelets it may be headed over slightly to prevent losing though permitting it to be punched out if required. 70

After inserting the cable the cable is tensioned to the pole by any desired tackle taking hold of the cable at a point just beyond the clamp, and after sufficiently tensioned the roller 14 is driven firmly into the wedge-like housing so as to grip 75 both the roller and the housing against any danger of slippage, in fact the greater the subsequent pull on the cable the better the roller grips.

Cotter pin 17 may then be passed through back of the roller as additional safety. A hole 80 19 is provided in the main shell 1 for punching the roller back if ever required to release the cable.

It will be noted that the slight flaring of the outer end of the cable channel at 20 permits vibration of the cable relative to the clamp without setting up objectional crystallization effects or scoring of the cable at that point. 85

When the clamps are in use on a transmission 90 line wire or cable as shown in Fig. 3 it will be seen that the coupling pin 4 is substantially in line with the pull or tensioned run of the cable, and that the inner run of the cable falls freely out of the line of tension.

95 It is evident from what has been described that the clamp may be made of any size or for more than one cable and that the roller is a form of wedge which may take other forms while still realizing other advantages of the invention.

We claim:

1. A cable strain clamp comprising an elongated body shell U-shape in cross section, and a cover plate for the open side of the shell removably secured thereto, a suspension connection at one end of said shell, said cover plate terminating in a position to permit deflection of a cable in a device away from said connection, and means within the body shell movable in a direc- 105 110 115

- tion generally longitudinally thereof for clamping the cable at a point within the body. 5. An elongated tubular body adapted to embrace a cable, an enlarged portion on one side only of said tubular body adjacent an end thereof forming a housing, means within said housing clamping the cable to the body and the tubular body formed with an extension on the end and on the side thereof opposite the housing adapting the cable to be diverted from its main run. 80
2. A cable strain clamp comprising an elongated body shell U-shape in cross section, and a cover plate for the open side of the shell, means holding the cover plate in place, an enlarged portion on said U-shaped shell forming a housing, means within the housing for clamping a cable within the body, and a coupling connection at the end of the body adjacent the clamping means. 6. In a structure as defined in claim 5, said means comprising a roller having a milled peripheral surface adapted to engage a side of the cable. 85
3. A cable strain clamp comprising an elongated body shell U-shape in cross section, and a cover plate for the open side of the shell, means holding the cover plate in place, an enlarged portion on said U-shaped shell forming a housing, means within the housing for clamping a cable within the body, and a coupling connection at the end of the body adjacent the clamping means substantially in line with the run of the cable through said body. 7. A cable clamp comprising a pair of elongated members each being U-shaped in cross section, said members arranged with their concave sides in parallel confronting relation and hinged together along one of their sides, removable means in the side opposite the hinge securing the members together with their concave sides in said opposed relation, one of said members provided with an enlargement at an end thereof forming a housing, means within said housing clamping a cable within the members and means at an end of the opposite member adapting the cable to be diverted from its main run. 90
4. A cable strain clamp comprising an elongated body shell U-shape in cross section, and a cover plate for the open side of the shell, means holding the cover plate in place, an enlarged portion on said U-shaped shell forming a housing, means within the housing for clamping a cable within the body, a coupling connection at the end of the body adjacent the clamping means substantially in line with the run of the cable through said body, and said cover plate formed with an extending end curved to guide the cable outwardly. 8. A cable clamp as defined in claim 7 provided with a suspension connection secured to the member that carries the means for clamping a cable within the members. 105

CERTIFICATE OF CORRECTION.

Patent No. 1,924,438.

August 29, 1933.

CHARLES W. KEMPER, ET AL.

It is hereby certified that error appears in the printed specification of the above numbered patent requiring correction as follows: Page 1, line 109, claim 1, for the article "a" read the; and that the said Letters Patent should be read with this correction therein that the same may conform to the record of the case in the Patent Office.

Signed and sealed this 5th day of November, A. D. 1935.

Leslie Frazer

(Seal)

Acting Commissioner of Patents.
